UNITED STATES PATENT OFFICE.

DAVID W. MILLER, OF CHICAGO, ILLINOIS.

EXCAVATING-MACHINE.

939,731.

Specification of Letters Patent. Patented Nov. 9, 1909.

Application filed January 8, 1907. Serial No. 351,347.

To all whom it may concern:

Be it known that I, DAVID W. MILLER, a citizen of the United States, residing at Chicago, in the county of Cook and State of Illinois, have invented certain new and useful Improvements in Excavating-Machines, of which the following is a specification.

This invention relates to improvements in excavating machines of that type in which the excavator is embodied in the form of a rotary wheel which is supported and carried along by a traveling wagon and progressively excavates a ditch in rear of the wagon.

Among the salient objects of the invention are to provide a machine of the character referred to, the excavator-wheel of which carries a series of combined scrapers and diggers which operate to loosen the soil and at the same time scrape it upwardly out of the ditch, thus dispensing with the usual buckets; to provide an excavator-wheel of such construction that its peripheral portions may be readily removed so as to very considerably reduce the diameter of the wheel for convenience in transportation and the like; to provide a construction in which there is combined with the scrapers certain diggers or cutters of peculiar construction and configuration; to provide in conjunction with the excavator-wheel an ejector operating to automatically wipe off each scraper blade as it passes the point of discharge; to provide in conjunction with a progressive excavating machine of the general character referred to a shield traveling with the excavator and operating to prevent the sides of the ditch or excavation from caving in temporarily, in order that tiling, masonry or other construction may be properly placed; to provide in conjunction with a wheel-excavator of this general character, a coöoperating relatively stationary apron and one or more traveling aprons which together serve to deliver the soil to a distance; to provide improvements in the details of construction and arrangement of the wagon whereby the excavator-wheel may be operated, raised and lowered, and otherwise manipulated, the wagon and excavator propelled slowly and at a rate suitable to effect continued excavation of a ditch, the wagon propelled at a second higher rate of speed when it is desired to transport the excavator from one place to another, and various other movements effected, all from one prime

mover and suitable driving connections therewith; to provide simplified and improved details of construction and arrangement in the frame construction both of the wagon and of the excavator-wheel, and its supports; and in general to provide an improved apparatus of the character referred to.

To the above ends the invention consists in the matters hereinafter described, and more particularly pointed out in the appended claims.

The invention will be readily understood from the following description, reference being had to the accompanying drawings, in which—

Figure 1 is a view chiefly in side elevation of a machine constituting a preferred embodiment of my invention; one of the transverse conveyer aprons being omitted to disclose other parts more clearly; Fig. 2 is a plan view of the machine; Fig. 3 is a fragmentary detail on a larger scale of a portion of the excavator-wheel; Fig. 4 is a transverse sectional view taken approximately on line 4—4 of Fig. 1 and looking in the direction of the arrows, omitting the excavator wheel; Figs. 5 and 6 are side and rear end elevations, respectively, of the shield; the latter figure showing the shield in operative position within a ditch; Fig. 7 is a fragmentary detail of one of the diggers of the excavating wheel shown in the preceding figures; Fig. 7^a is a perspective detail of one of the spring teeth or diggers; Fig. 8 is a detail cross sectional view taken on line 8—8 of Fig. 3, viewed in the direction of the arrows; Figs. 9 and 10 are a plan view and a side elevation, respectively, of the preferred driving mechanism shown in Fig. 1.

In the wheel-excavators of the prior art, so far as I understand the same, buckets of one form or another have always been deemed necessary to scoop up the soil and carry it to the discharging level, and much difficulty has been experienced in effecting the proper discharge of the buckets, particularly in clay soils. Moreover the mechanism for supporting and discharging the buckets has been complicated, expensive and more or less subject to breakage and disarrangement.

Excavator-wheels of the general type to which this invention pertains must ordinarily be constructed of relatively large di-

ameter in order that they may excavate to a sufficient depth, it being obvious that such a wheel can only excavate to a depth approximately one-half its diameter. Owing to the necessary weight of a wheel of such relatively large diameter, great difficulty is experienced in loading the apparatus upon cars and otherwise transporting the machine. These machines are frequently used in soils which are either sandy or largely composed of loose loam,—in fact they find their most useful field in soils of these characters, and much difficulty has been experienced due to the caving in of the sides of the ditch before it can be utilized for its intended purpose. These and other objections I overcome in the present invention, as will appear from the following description.

Referring to the drawings, 1 designates as a whole a suitable wagon or operating truck, 2 designates as a whole the excavator-wheel, and 3 a shield which may or may not be used in conjunction with the excavator, but when used trails along in the ditch immediately in rear of the wheel.

Describing first the excavator-wheel, the latter desirably comprises an inner ring 4 of I-beam form in cross section (see Fig. 3), a suitable series of spokes 5 connecting the inner rim with the hub 6, and a plurality of detachable segmental sections 7 mounted upon the exterior of the ring 4. The frame structure of each segment 7 comprises a skeleton segmental shaped frame 8 desirably formed of structural bars T-shaped in cross section and with the central web or flange extending inwardly from each margin of the frame, a series of transverse rods 9 upon the outer periphery of each segment at suitably spaced intervals, corresponding pairs of brace-rods 10 (see Fig. 8) connected with the outer ends of the respective rods 9 and converging inwardly to, and connected with, the web of the inner portion of the frame 8, and flat segmental bars 11 applied to the opposite sides of each segment frame and through which the ends of the rods 9 extend. Each segment frame is detachably bolted to the outer face of the inner ring 4, as seen clearly in Fig. 3, and the abutting ends of the segments are likewise detachably bolted together so that the segments may be removed from the wheel at will.

12, 12, designate a pair of boom members arranged to support the excavator wheel, each member 12 carrying at its rear end a journal box 13 within which extends the corresponding end of the axle 14 of the wheel. At their opposite ends the boom members are connected with an upstanding strut-frame 14 of inverted U-shape (see Fig. 4), and the upper portions of said strut-frame are connected with the respective boom members 12 at points adjacent to the wheel hub by means of tension bars 15. The lower end

of the strut-frame is formed by a transverse rock bar 16 which is journaled in suitable bearing supports 17 mounted upon the main side frame members of the wagon 1 near the rear end of the latter. The strut-frame, and with it the excavator-wheel supported thereby, is oscillated by means of mechanism hereinafter described.

Describing now more particularly the construction of the several diggers and scrapers forming part of the wheel, and referring to Fig. 3, upon each segment 7 is mounted a plurality of yieldable scrapers 18, one or more fixed or rigid scrapers 19, and one or more diggers 20; the yieldable scrapers, the fixed scrapers and the diggers being suitably interspaced, as seen clearly in said figure. Each yieldable scraper comprises a flat blade 21 (see Fig. 8) arranged nearly radial with reference to the axis of the wheel but inclined rearwardly somewhat, cut out or notched at its central portion, as indicated at 22, to straddle the outer marginal frame of the segment and pivotally mounted upon the corresponding cross rod 9 by means of suitable strap-eyes or bearings 23. Each scraper blade is of the full excavating width of the wheel, and its outer margin forms the scraper proper which gathers the soil and pushes it ahead of the scraper during the rotation of the wheel. The inner end of each yieldable scraper blade terminates about mid-width of the segment and is yieldably connected with a part of the segment frame in rear thereof by means of coiled springs 24. Each scraper blade furthermore carries a series of spring-teeth or diggers 25 which are shaped much like the spring harrow teeth in common use and are so arranged that their outer free ends project radially beyond the margins of the corresponding scraper blades a short distance and are located in rear of the latter somewhat, as seen clearly in Fig. 3. These spring-teeth are spaced apart at frequent intervals (see Fig. 8), and the teeth of one scraper are offset or out of circumferential alignment with those of the succeeding scraper. Moreover the laterally outermost teeth of each scraper blade are set some distance inwardly from the corresponding margins of the scraper blade for a purpose which will hereinafter appear.

The rigid scrapers 19 are constructed and mounted in substantially the same manner as those last described except that instead of having their inner ends connected by springs with the wheel-frame, they are extended inwardly and bolted to the flange of the angle member 8, as indicated at 26. The diggers 20 are also rigidly connected with the wheel-frame and are set more exactly radial than the scrapers. These diggers are formed of strap-steel bent into suitable shape to form an outer loop or cutter 27 (see Fig. 7), a main body or shank 28 formed integrally

with the cutter and a brace-bar 29 connected with the inner end of the cutter loop and extending thence obliquely inwardly and forwardly to, and connected with, the 5 inner ring of the wheel. The inner ends of the shank or body members 28 are bolted to the flange of the ring member 8. As will be clear by reference to Fig. 3 these diggers are set at varying distances from the median 10 line of the wheel, *i. e.*, they are circumferentially offset relatively to each other and collectively cut practically the full width of the wheel. The wheel is provided with sprocket teeth 30 extending entirely around 15 its outer periphery and located midwidth of the wheel, as best indicated in Fig. 8, and a sprocket chain belt 31 trained around the wheel and around a driving sprocket 31' mounted upon the strut-frame (see Figs. 1 20 and 4) serves to rotate the wheel as will now be described.

The drive-sprocket 31' is sleeved to a companion sprocket 32 and the two mounted upon a suitable shaft 33 extending across 25 the strut-frame. The sprocket 32 is driven by a belt 34 from another pair of sprockets 35 and 36 similarly sleeved together and journaled upon the rock-shaft 16. Sprocket 36 is driven by a belt 37 which leads forwardly to, and is connected with, a sprocket 38 mounted upon a transverse shaft 39 suitably journaled upon the wagon. Shaft 39 is driven from a main shaft 40 which is journaled to extend longitudinally of the 35 wagon; the bevel-gear 41 on said main shaft serving to transmit motion to a second bevel-gear 42 on shaft 39. A clutch 43 controlled by a bell-crank-lever 44, hand lever 45 and connecting rod 46, serves to throw the 40 sprocket 38 into and out of gear with shaft 39.

For raising and lowering the excavating-wheel, so as to vary the depth of cut or elevate the wheel for transportation, tension-links 47 (see Fig. 1) are connected with the upper end of the strut-frame 14, and with the ends of these links are connected winding cables 48 which extend to, and are wound upon, a pair of windlass drums 49 mounted 50 upon a cross-shaft 50 journaled in the main frame of the wagon. Shaft 50 carries a worm-gear 51, the upper periphery of which is engaged and actuated by a worm-shaft 52, which is in turn driven by a sprocket 53, 55 mounted thereon. Sprocket 53 is connected with another sprocket 54 on the main shaft by a sprocket-belt, and the sprocket 54 is controlled by a clutch 55 and hand-lever 56 for operating the same.

60 For propelling the machine along slowly, so as to excavate a ditch progressively, and for propelling the machine at a more rapid speed when transporting it from place to place, driving connections are provided as 65 follows: Upon the main shaft 40 is mounted

a sprocket 57 which is belted to a sprocket 58 upon a worm-shaft 59 carrying a worm 60. The worm actuates a gear 61 upon a transverse shaft 62, which latter is provided at one end with a pinion 63 which meshes 70 with a gear 64 upon another transverse shaft 65. Shaft 65 carries at each end pinions, as 66, 67, which engage and drive relatively large spur-gears 68 upon the main traction wheels 69. This is the low speed drive. 75

For propelling the machine more rapidly, shaft 62 is driven from the shaft 39 through the medium of a sprocket 70 mounted upon said shaft and belted to another sprocket 71 upon the shaft 62. The driving connections 80 between gear 61 and shaft 62 and between sprocket 71 and shaft 62 are controlled by means of a pair of clutches 73 and 74, respectively; the movable members of these two clutches being linked together as indicated at 75 and actuated by a bell-crank 76 and hand-lever 77. The arrangement is such that the clutches are thrown into gear alternatively, and when the clutches are in the intermediate position shown in Fig. 2 90 both are out of gear. A differential gear mechanism 78 is interposed in the shaft 65; the center member of this differential being engaged and driven by the spur-gear 63.

In addition to the mechanism thus far 95 described for operating the excavator and propelling the machine, mechanism is provided for conveying the soil laterally outward from the delivery point of the excavator-wheel to points at each side of the 100 ditch. To this end a pair of laterally extending wing-like frames 79 (see Fig. 4) are suitably supported from the strut-frame and main wagon frame in upwardly and outwardly inclined position; these frames 105 each carrying a set of belt-rollers, as 80, 80 and 81, 81, around which are trained conveyer belts 88. The lower ends of the belt-frames approach each other as closely as practicable without interfering with the 110 movement of the belts, and the lower rolls 81 are positively driven so as to actuate the belts. To this end driving connections from the main shaft comprise a sprocket 82 mounted upon the latter and controlled by 115 a clutch 83, a counter-shaft 84 journaled in the lower part of the wagon-frame and forming the shaft upon which one of the rollers 81 is mounted, a sprocket 85 upon shaft 84 belted to the sprocket 82, a parallel 120 shaft 84' constituting the shaft upon which the companion drive roller 81 is mounted, and spur-gears 86, 87, operatively connecting shafts 84 and 84'. The main shaft is rotated by a pair of engines 89 mounted 125 upon the wagon frame which receive steam from a boiler 90 also carried by the wagon.

The traveling aprons or conveyer belts 88 are located some distance in front of the forward periphery of the excavator-wheel, 130

and in order to conduct the soil from the excavator-wheel to the conveyers, a receiving apron or chute 91 is suitably suspended from the main wagon-frame by means of 5 hinges or links 92, with its rear end located as close to the periphery of the excavator-wheel as practicable and its forward end overhanging the aprons. Ordinarily this 10 apron will be in upwardly and forwardly inclined position, as shown in Fig. 1; the arrangement being such that the soil discharged from the ditch by the upwardly moving scrapers of the excavator is deposited upon the apron 91 and gradually 15 accumulates and is pushed upwardly and forwardly across the latter until it discharges upon the traveling aprons.

In order to insure the discharge of the soil from the scrapers onto the apron 91 I provide 20 an ejector, designated as a whole 93; this ejector comprising a blade 94 of a length somewhat greater than the face width of the excavator-wheel, and bail-arms 95, 95', at each end thereof, the ends of which are pivotally 25 connected with the boom members 12 (see Fig. 3) in such manner that the ejector embraces the outer periphery of the excavator-wheel and springs pendulously upon its pivotal supports. The position of its 30 pivotal bearings 96 is such that when the ejector springs downwardly its blade swings inwardly in front of the rising scrapers and diggers, and as the scrapers encounter the lower edge of the ejector-blade the latter is 35 lifted and thus wipes across the face of each scraper, and discharges the soil therefrom. As the ejector reaches a position approximately 40 upon a level with its pivotal supports its lower edge passes out of engagement with the scraper, then lifting it, and the latter passes through or between the bail-arms of the ejector. In order that the lower edge of the ejector may not catch upon the points 45 of the spring digger teeth 25, the lower corners of the ejector-blade are provided with heel-like extensions 97 which serve to carry the main blade of the ejector radially outside of the path of the said teeth, and it is to avoid interference with these extensions 50 97 that the teeth 25 are set inside of the lateral edges of the scraper blades, as hereinbefore referred to and as seen in Fig. 8.

As a further feature of improvement, I provide a shield which is connected with the 55 axle of the excavator-wheel and trails behind the latter within the ditch to prevent caving in of the latter. This shield, in the preferred form shown, comprises a pair of relatively thin sheet metal blades 98 spaced 60 apart and suitably united with each other by means of jack-rods 99; one end of each rod being formed with telescoping portions which are held yieldably extended upon each other by means of coiled expansion springs 65 100 (see detail Fig. 6). Jack-screws 101

serve to adjust the length of these rods so as to space the shield-blades the right distance apart. The jack-rods are so spaced apart as to provide room for an operator to lay tiling or masonry in the ditch between the 70 shield blades. In order to draw the shield along, it is provided at each side with a draft-link 102, which draft-links are pivotally connected with the axle of the excavator-wheel. 75

The machine may be steered in any suitable manner. In the preferred construction shown the front axle 103 is pivotally connected with the main frame, as indicated at 80 104, and steering cables 105 connected with the respective ends of the axle lead rearwardly to, and are connected with, winding drums 106 mounted upon a cross-shaft 107; the cables being oppositely wound upon the drums. Shaft 107 carries a worm-gear 85 which is actuated by means of a worm upon the steering shaft 108; the latter being provided with the usual hand-wheel 109.

The operation of the apparatus constructed as described has been fully and clearly indicated in connection with the description of the mechanism, and need not therefore be repeated. It may be noted, however, that the soil is loosened and dislodged by the spring digger teeth 25 and cutters 20, and 90 is scraped upwardly out of the ditch by the series of scrapers. Should the spring teeth encounter roots or stones of small size, they will yield and thus avoid breaking the teeth, while the cutters, by reason of their peculiar 95 shape, will cut off the roots and dislodge the stones if not too large, after which they will be scraped out by the scrapers. It is to be particularly noted that the construction of the frame-work of the excavator wheel is 100 such as to secure great strength with a minimum weight. 105

I claim as my invention:

1. In a wheel-excavator, the combination with a wheel frame, of a series of scraper 110 blades mounted upon the periphery of the wheel and arranged approximately radial thereto, and diggers interposed between the scrapers and projecting radially beyond the acting edges of the latter. 115

2. In a wheel-excavator, the combination with a wheel frame, of a series of scraper blades mounted upon the periphery of the wheel and arranged approximately radial thereto, and a plurality of spring digger 120 teeth mounted upon or contiguous to each scraper blade and projecting at their acting ends radially beyond the scraper blades. 125

3. In a wheel excavator, the combination with a wheel frame, of a series of scraper blades mounted upon the periphery of the wheel and arranged approximately radial thereto, and a plurality of spring digger teeth mounted upon or contiguous to each scraper blade and projecting at their acting 130 ends. 135

ends radially beyond the scraper blades, each of said spring teeth having the form of flat strap-like members convexly curved with their convexity toward the rear and their points 5 inclined forwardly and radially outward.

4. In a wheel-excavator, the combination with a wheel frame, of a series of scraper blades mounted upon the periphery of the wheel, arranged approximately radially thereto and extending transversely with reference to the face of the wheel, each scraper blade being pivotally mounted intermediate 10 its length, and a series of springs yieldably connecting its inner end with an adjacent 15 part of the wheel frame.

5. In a wheel excavator, the combination with a wheel frame, of a series of yieldable scraper blades mounted upon the periphery of the wheel and arranged approximately 20 radially thereto, a plurality of rigid scraper blades similarly mounted upon the wheel frame and interposed between the yieldable scraper blades, and diggers arranged at intervals apart around the periphery of the 25 wheel frame and between the scraper blades.

6. In a wheel-excavator, the combination with a wheel frame, of a series of scraper blades mounted upon the periphery of the wheel and arranged approximately radially thereto, and a plurality of cutters mounted 30 upon the wheel frame and projecting radially beyond the acting edges of the scrapers, each cutter consisting of an open loop cutting portion, a shank or support, and a 35 brace-bar.

7. In a wheel-excavator, the combination of an inner wheel-frame, a circumferentially disposed set of segment frames detachably mounted upon said inner wheel frame, and 40 excavating devices mounted upon the several segments.

8. In a wheel excavator, the combination of an inner wheel frame of skeleton construction, having a peripheral ring of angled structural iron, a series of outer segments mounted upon said inner wheel frame and detachably connected with said angled ring, each 45 segment comprising a skeleton frame member, and a series of excavating devices 50 mounted upon each segment.

9. In a wheel-excavator, the combination with a wheel frame provided at its periphery with a series of scrapers and a supporting frame within which said excavator-wheel is suspended, of an ejector pivotally mounted upon said supporting frame adjacent to the periphery of the excavator-wheel and adapted to successively engage and wipe 55 across the advance surface of the scrapers as 60 the latter are rotated past its point of support.

10. In a wheel-excavator, the combination with a wheel frame provided at its periphery with a series of scrapers having the form 65 of flat blades arranged approximately radi-

ally with reference to the axis of the wheel and a supporting frame upon which said wheel is mounted, of an ejector comprising a transversely disposed blade and bail-arms connected with each end of said blade, and 70 pivots connecting said bail-arms with said supporting frame at each side of the excavator-wheel in position to permit the periphery of the wheel to pass between the bail-arms and the blades of the ejector to engage 75 and wipe across the forward faces of the scrapers.

11. In a wheel-excavator, the combination with a wheel frame and a series of scraper blades mounted upon the periphery of the wheel and arranged approximately radially thereto, of a supporting frame comprising boom-arms between which said excavator-wheel is supported to rotate, and an ejector 80 consisting of a transversely disposed ejector blade and bail-arms connected with each end of said blade, and pivots connecting said bail-arms with said boom members at points laterally opposite the respective sides of the 85 excavator-wheel and radially inside of the periphery thereof, whereby the ejector blade is successively engaged by the scraper blades and oscillated upwardly until the ejector blade passes over and outside of each scraper 90 blade. 95

12. In a wheel-excavator, the combination with a wheel frame and a series of scrapers mounted upon the periphery thereof, of a stationary apron supported adjacent to the 100 uprising periphery of the wheel in position to receive the soil scraped upwardly out of the excavation.

13. In a wheel-excavator, the combination with a wheel frame and a series of scrapers mounted upon the periphery thereof, of a 105 receiving apron supported adjacent to the uprising periphery of the wheel in position to receive the soil scraped upwardly out of the excavation, and one or more transversely disposed traveling conveyers arranged to 110 extend beneath the delivery end of said receiving apron.

14. The combination, with an excavating wheel and means for advancing the same in the direction of its own plane, of a pair of 115 inclined transversely disposed conveyer belts having their lower ends arranged in advance of the ascending side of the excavating wheel, slightly above the ground level, and inclining outwardly and upwardly; means for supporting and driving said conveyers; and a stationary apron arranged to conduct the material from the excavating wheel on to the receiving ends of said conveyers. 120 125

15. In a wheel-excavator the combination, with the excavating wheel, of a shield comprising a pair of upright plates arranged in the rear and at the sides of the excavating wheel, said plates being connected by 130

transverse telescopic jack-rods, and draft-links pivotally connecting said shield with the axle of the excavating wheel.

16. In a wheel-excavator the combination, 5 with the excavating wheel, of a shield comprising a pair of upright plates arranged at the rear and sides of the excavating wheel, said plates being connected by transverse jack-rods provided with length-adjusting screws and expansion springs; and draft rods pivotally connecting said shield with the axle of the excavating wheel.

17. In a wheel excavator the combination, 15 with a suitable wagon, of a strut-frame pivotally mounted at its lower end upon the wagon, an excavating wheel and axle, a pair of booms connecting the lower portion of the strut frame to said axle, tension members connecting the top of the strut-frame 20 to said booms adjacent said axle, and means for tilting the strut-frame to raise or lower the excavating wheel.

18. In a wheel excavator the combination, 25 of a suitable wagon located in advance of said wheel, a strut frame pivotally mounted at its lower end upon said wagon, an excavating wheel and its axle, a pair of booms connecting the lower portion of the strut frame to said axle, tension members connect- 30 ing the top of the strut frame to said booms adjacent said axle, excavating wheel drive gearing carried by the strut frame, and means, substantially as described, for tilt- 35 ing the strut frame for raising or lowering the excavating wheel.

19. In a wheel-excavator the combination, 40 of a suitable wagon, a motor forwardly positioned thereon, a longitudinally extending power shaft driven directly from the motor, an excavating-wheel operating mechanism, a wagon-propelling mechanism, and a conveyer-driving mechanism, said mechanisms being separate and independent of one another, and independently operable driv- 45 ing connections between said mechanisms and said longitudinal power shaft.

20. In a wheel-excavator the combination, 50 of a suitable wagon, a motor forwardly positioned thereon, a longitudinally extending power shaft driven directly by the motor, excavator-wheel driving mechanism, a conveyer-driving mechanism, said mechanisms being separate and independent of each other, and independently operable driv- 55 ing connections between said mechanisms and said longitudinal power shaft.

21. In a wheel-excavator the combination, 60 of a suitable truck, a motor forwardly positioned thereon, a longitudinally extending power shaft driven directly by the motor, an excavating-wheel operating mechanism, a truck-propelling mechanism, said mechanisms being separate and independent of each other, and independently operable driving

connections between said mechanisms and 65 the longitudinal power shaft.

22. In a wheel-excavator the combination of a suitable wagon, an excavating-wheel in rear thereof, a longitudinal power shaft mounted on the wagon, a transverse shaft 70 driven from said power shaft, a drive-wheel on said transverse shaft, a belt driven by said drive-wheel for driving the excavator-wheel, and a clutch for starting and stopping the excavating-wheel while said 75 power shaft is in motion.

23. In a wheel-excavator the combination of a suitable wagon, provided with traction wheels, a transverse shaft provided with drive-pinions for said traction wheels, a 80 second transverse shaft, an equalizing gear mounted on one of said shafts and geared to the other, a longitudinally extending power shaft, a worm gear for driving said second shaft and traction wheels at slow speed, 85 driving connections between said worm gear and the power shaft, gearing driven by the power shaft for driving said second shaft and traction wheels at a higher speed, and means for placing either the high or the low 90 speed gear in operative connection with said second shaft.

24. In a wheel-excavator the combination of a suitable wagon, an excavating-wheel in rear thereof, a frame for carrying and guiding the excavating-wheel said frame being pivoted on the wagon and comprising an upwardly extending arch-shaped member, a transverse shaft mounted on the wagon, a windlass-drum fixed upon said shaft, a 100 longitudinally extending power shaft, driving gears connecting said power shaft with the windlass-shaft, and a cable connecting the windlass-drum with the upwardly extending member of the excavating-wheel 105 frame, the winding or unwinding of said cable raising or lowering the excavating-wheel through the medium of said frame.

25. In a wheel-excavator the combination of a suitable wagon, a longitudinally extending power shaft mounted thereon, a 110 longitudinally disposed conveyer-drive-shaft positioned below said power shaft and extending rearwardly toward the excavating-wheel, a transversely disposed endless conveyer driven from the last-named shaft, gearing between said shaft and the power shaft, and a clutch for starting and stopping said conveyer while the power shaft is in motion.

26. In a wheel-excavator the combination of an excavating wheel and its axle, a suitable wagon located in advance of said wheel, an inverted U or arch-shaped frame pivotally mounted on a transverse axis upon the 125 wagon, suitable braces, booms connecting the lower part of said frame to the axle of the excavating-wheel, and means, operated from

the wagon, for tilting said frame to raise and lower the excavating-wheel.

27. In a wheel-excavator the combination of an excavating wheel and its axle, a suitable wagon in advance of said wheel a transverse shaft mounted on the rear portion of the wagon, a tilting inverted U or arch-shaped frame having its lower ends mounted pivotally on said shaft, booms connecting the lower part of said frame to the axle of the excavating-wheel, suitable braces, and

mechanism for driving said excavating-wheel, said mechanism including sprockets journaled on said shaft, other sprockets carried by said frame, a drive-belt trained around one of said sprockets and the excavating-wheel, and means for driving said sprockets on said first-named shaft. 15
